[57] CLAIM

The ornamental design for a combined toy stuffed
stegosaurus dinosaur and egg container, as shown.

DESCRIPTION

FIG. 1 is a perspective view of a partially open com-
bined toy stuffed stegosaurus dinosaur and egg con-
tainer embodying my new design;

FIG. 2 is a front elevational view thereof, the rear view
being a mirror image view thereof;

FIG. 3 is a bottom plan view thereof;

FIG. 4 is a top plan view thereof;

FIG. 5 is a perspective view thereof with the dinosaur
figure fully emerged from the egg container;

FIG. 6 is a left side elevational view thereof;

FIG. 7 is a right side elevational view thereof;

FIG. 8 is a front elevational view thereof;

FIG. 9 is a rear elevational view thereof;

FIG. 10 is a top plan view thereof; and,

FIG. 11 is a bottom plan view thereof.
